ART OF DRYING VARNISHED SURFACES

John J. Brophy, Salem, Mass., assignor to The Turner Tanning Machinery Company, Portland, Maine, a corporation of Maine

Application May 9, 1933, Serial No. 670,143

23 Claims. (Cl. 34—12)

This invention relates to the treatment of sheet material to a surface of which coloring matter or coating material, such as ink or varnish, has been applied. While the invention is 5 illustrated with reference to a machine especially constructed for the treatment of varnished surfaces on pieces of leather, it is to be understood that the invention and various important features thereof may have other applications 10 and uses.

It is an object of this invention to utilize to the best advantage ultra-violet radiation from any suitable source in drying operations upon colored or coated surfaces on sheet material. Since 15 radiation which falls perpendicularly, or substantially so, to the surface of the work is most effective, provision is made by my invention for so positioning and moving the work relatively to the source of ultra-violet radiation that a maximum 20 proportion of the ultra-violet radiation strikes the varnished surfaces along lines perpendicular thereto. At the same time the spacing of the source of ultra-violet radiation with respect to the surface to be treated is maintained 25 as small as possible since the intensity of the effect of the radiation is greater the shorter the distance between said surface and the source of radiation. It is a further object of the invention to utilize the ultra-violet radiation to the maximum 30 extent by keeping the work pieces in close juxtaposition to each other, it being clear that radiation is wasted upon spaces between pieces of work as the latter travel past the source or sources of radiation.

With the above and other objects in view, and in accordance with an important feature of the invention, means is provided for moving pieces of work in a circular or cylindrical path around a source of ultra-violet radiation and at a minimum 35 distance therefrom. As illustrated the described means comprises a flexible conveyor mechanism arranged to travel around a source of radiation in an arc of substantially 300° struck from the center of said source of radiation whereby as large a proportion as is practicable of the radiation strikes the varnished surfaces along lines perpendicular to said surfaces, this being the most effective radiation.

It is an important feature of the invention that 40 means is provided for holding pieces of work in place upon the flexible conveyor without the use of fastening devices, the use of which would necessitate spacing between adjacent pieces of work, and the application of which would require 45 the expenditure of considerable time and labor.

As illustrated the improved means comprises an air suction apparatus whereby atmospheric pressure is depended upon for holding the work pieces in place, the conveyor being especially constructed for this purpose of foraminous material 5 so that the work pieces may be held thereagainst through the operation of said air suction means.

In the illustrated machine, specially designed for the treatment of pieces of patent leather, the source of ultra-violet radiation is a horizontally 10 arranged lamp to which the pieces of leather are presented by a horizontally traveling conveyor mechanism adapted to receive pieces of leather placed loosely thereon in close juxtaposition to each other, and to carry said pieces past the 15 lamp in closely spaced relation thereto while the pieces of leather rest upon the conveyor unattached to each other or to the conveyor and free from any fastening devices. As illustrated, the horizontally arranged conveyor mechanism 20 is guided and moved in such manner as to pass through an arc of substantially 300° with the lamp at the center axis thereof. As shown the lamp is located in a chamber from which the air may be withdrawn by means constantly operating to that end whereby each piece of leather, though free from the conveyor, is held stationary 25 with respect to the conveyor in fully spread out condition thereon during all of its travel about the lamp.

These and other important characteristics and features of the invention and novel combinations of parts will now be described in detail in the specification and then pointed out more particularly in the appended claims.

In the drawings,

Fig. 1 is a view in side elevation and partly in section of a machine showing one embodiment of the invention;

Fig. 2 is a sectional view taken along the lines 40 II—II of Fig. 1 looking in the direction of the arrows;

Fig. 3 is a vertical sectional view taken along the line III—III looking in the direction of the arrows;

Fig. 4 is a sectional view along the line IV—IV of Fig. 2; and

Fig. 5 is a diagrammatic view illustrating the direction of radiation from the lamp.

In the illustrated machine, which is particularly designed for treating patent leather surfaces, there is provided a horizontally arranged lamp 10 conveniently of the type known as a gaseous discharge lamp energized by induction and operating on a high tension current. The 55

lamp tube is of quartz and is sealed after introducing a small amount of mercury, to serve as the active agent in producing the ultra-violet radiation, and a small amount of argon at the proper pressure to assist in starting ionization of the mercury vapor. At one end of the lamp 10 is a coil 11 for carrying water to keep the temperature of the lamp down and to maintain gas pressure at a value for efficient operation of the lamp. Surrounding the lamp 10 is a quartz envelope 12 cylindrical in form and open to the air at each end. The purpose of this envelope will be described later in the specification. Outside of the envelope 12 is a coiled copper tube 14 serving as an inductor element, the tube 14 being a long ellipse in cross section so as to leave as much space as possible between the turns of the coil. The purpose of this copper coil is to carry a high frequency current from an oscillation generator, not shown, the action of this coil being to induce current in the gases of the lamp.

In the illustrated machine, which has operated effectively and satisfactorily in practice, the lamp inductor coil 14 is about sixty inches long and comprises one hundred twenty equally spaced turns, the conductor being made of $\frac{1}{4}$ " copper tube flattened into an ellipse in cross section and wound upon the quartz envelope 12 which is spaced about one-half inch from the periphery of the lamp tube 10.

The inductor is supplied with high frequency current from the oscillation generator, satisfactory operation having been secured in practice with a frequency of about 12,000 kilocycles, an average current value of the order of 45 amperes, and a potential of approximately 15,000 volts. These values are given for the purpose of illustration only and may be varied according to circumstances to secure the most effective and efficient operation under any given conditions. I believe that the maximum efficiency of the apparatus is secured under normal conditions when the impedance of the lamp inductor circuit approximates as closely as possible that of the oscillator tubes. I also believe that, in conducting the high frequency current from the oscillation generator to the lamp inductor coil, more efficient operation can be secured by using flat parallel conductors. This will tend to avoid local inductive effect.

The energy imparted to the lamp produces ultra-violet radiation. This lamp, operated as above indicated, is particularly efficient since the greater part of the ultra-violet radiation therefrom falls within a relatively narrow band extending from about 2500 to 3500 Angstrom units, radiation within this band being the most effective in the treatment of varnished surfaces to dry the same. Furthermore, there is relatively little radiation in the longer wave lengths manifested as heat. The copper coil 14 is a tube which carries a constantly flowing stream of water in order to prevent the copper from being melted by the relatively intense heat which otherwise would be developed in this copper conductor. As shown the copper coil 14 has its terminals 16 and 18 arranged in parallelism as shown in Fig. 3.

In order to utilize ultra-violet radiation to the best advantage it is desirable that as large a proportion as possible of such radiation should strike the varnished surface to be treated along lines perpendicular thereto, as indicated in Fig. 5, wherein lines 37 indicate the direction of radiation from lamp 10 to the varnished surface of a piece of work 39 traveling in a circular path

about said lamp. For this reason means is provided for moving the pieces of work around the lamp in a path which is an almost closed cylinder, that is, as illustrated, through an arc of about 300° . As shown, this means comprises a conveyor belt 40 guided to move in said arc. Conveniently, this conveyor belt is composed of a woven wire mesh 42 fastened continuously along each edge to link belt conveyor chains 44, the latter being arranged to engage with sprocket wheels 46 upon shafts 48 and 49. As shown, the shafts 48, 49 (Fig. 1) are mounted in the frame of the machine below the level of horizontally arranged tables 50, 51 said shafts carrying rollers 52 which extend the full width of the machine and serve as supports and feeding means for the wire mesh portion 42 of the conveyor while the sprockets 46 serve as supports and feeding means for the link chains 44 at each edge of 20 the mesh. In addition to passing around the sprockets 46 the link chains 44 are also engaged with a pair of sprocket wheels 54 (Fig. 1) upon shafts 56 and with a larger sprocket wheel 58 (Figs. 1 and 4) by which the conveyor is carried 25 in a cylindrical path the axis of which corresponds to the axis of the lamp 10, the sprockets 54 co-operating with the larger sprockets 58 to guide the link chains and the attached woven wire mesh 42 along a path which approaches 30 as near as is practicable to a closed cylinder of about ten inches in diameter. Conveniently and as shown, the sprocket wheel 58 at each end of the lamp chamber consists of an annular member having sprocket teeth upon its outer periphery, the inner periphery of said annular member being receivable within a groove in a stationary supporting member 60 (Figs. 3 and 4) made preferably of a non-conducting substance such as bakelite, said member 60 being attached 40 to wooden struts 62 constituting part of the machine frame. Upon reference to Fig. 4 of the drawings it will be observed that the conveyor 40 is an endless conveyor and that it is guided in the lower run thereof by idler rollers 45 10 also mounted in the machine frame and extending clear across from one side thereof to the other.

Means is provided for driving the shafts 48, 49, the said means comprising in the illustrated construction an electric motor 72 (Figs. 1 and 2) having an armature shaft 74 provided with a worm 76 arranged in mesh with a worm gear 78 mounted upon a shaft 80 supported in the machine frame. Fastened to the said shaft 80 is 55 a sprocket wheel 82 around which passes a sprocket chain 84 also engaged with a sprocket 86 on a shaft 88 to which is fixed a second sprocket wheel 90 about which passes a sprocket chain 92 which passes around a larger sprocket wheel 60 94 secured to the shaft 48 to serve as a driving means therefor. Fastened to the shaft 48 is a sprocket wheel 96 about which passes a sprocket chain 98 also engaged with a sprocket wheel 100 fastened to the shaft 49, the arrangement being 65 such that both shafts 48 and 49 are driven in the same direction to cause travel of the conveyor comprising the wire mesh 42 and the link chains 44.

Means is provided for holding the pieces of 70 leather upon the wire mesh conveyor 40 while it is traveling in reverse curves around the lamp 10, said means comprising in the illustrated construction an air suction chamber 110, the walls 112 of which are made of sheet metal, as most 75

clearly shown in Fig. 4. Preferably and as shown an upper wall 114 of the chamber 110 is constructed to conform to the wire mesh conveyor in that portion of its run between the rollers 52, the construction being such that the sheet metal of the upper wall 114 of the chamber 110 and of cylindrical wall 116 of the lamp chamber are pervious to air through the provision of a multiplicity of perforations through which the air may pass, the amount of air passing through said perforations being variable with the size and shape of the leather in place upon the wire mesh conveyor. To provide a suction effect for the purpose of holding pieces of leather upon the mesh conveyor there is provided means for withdrawing air from the chamber 110, the said means comprising a blower 120 (Figs. 1 and 2) having a conduit 122 extending therefrom, said conduit dividing into two pipes 124, the pipes 124 opening into opposite ends of the chamber 110 at opposite sides of the machine. Upon reference to Figs. 3 and 4 it will be seen that the pipes 124 open into a lower part of the chamber 110 as at 126 (Fig. 4) at opposite ends thereof. The air pressure upon the pieces of leather traveling along the wire mesh conveyor 40 is sufficient to hold them firmly on the conveyor while they are passing around the lamp 10.

For conveying pieces of leather to the described wire mesh conveyor 40, there is provided a feeding mechanism comprising a plurality of relatively narrow belts 130 (Figs. 1 and 2) the upper run of which rests upon the table 50, the belts 130 passing around crown portions 134 of an idler roll 136. At their other ends the belts 130 pass over crown portions 138 of a driven roll 140 mounted upon the frame of the machine and having fixed thereto at one end a sprocket wheel 142 (Fig. 1) arranged to be driven by a sprocket chain 144 passing over a sprocket 146 on the driven shaft 49 around the roller 52 of which the wire mesh conveyor passes. For guiding the pieces of work from the conveyor belts 130 to the wire mesh conveyor 40 there is provided (Figs. 2 and 4) a short table 150.

Conveniently, and as shown, a delivery mechanism is provided for carrying the pieces of work away from the wire mesh conveyor 40 after treatment by the lamp 10, the said delivery mechanism comprising a short delivery table 152 and belts 160 (Figs. 1 and 2) passing over the table 51 and driven by crowned portions 164 of a roller 166, the shaft 168 (Fig. 1) of which carries a sprocket 170 arranged to be driven by a sprocket chain 172 in turn driven by a sprocket 174 on the driven shaft 48. At their other ends the belts 160 pass over crown portions 180 of an idler roll 182 rotatably mounted in the frame of the machine. Both the sets of belts 130 and 160 may be provided with belt tighteners such as the pivoted members 184 (Figs. 1 and 2) carrying at their ends idler rolls 186 arranged to rest upon the lower runs of the belts.

In the manufacture of patent leather a "daub" coat is applied to a piece of leather while the latter is maintained in stretched condition on a frame. This first "daub" coat may be allowed to dry although it is usually baked in an oven. Subsequently several other "daub" coats are applied and the baking repeated with each coat. Finally a "finish" coat of varnish is applied and the leather placed in an oven where it is baked usually for a period of fourteen hours or more at a temperature of about 160° F. Following

this operation it has been common practice to subject the patent leather surfaces to solarizing in the open air, the purpose being to complete the drying of the varnished surfaces to such an extent at least as to reduce to the desired degree the sticky or tacky condition which persists even after prolonged baking. Since the "daub" and "varnish" coats of different batches of patent leather vary considerably, even in the same plant, the treatment of the varnished surfaces by ultra-violet radiation from natural or from artificial sources must be carried out for various periods of time. Hence in the illustrated machine means is provided for driving the conveyor mechanism at several selected speeds so that the leather may be moved at different rates past the lamp. The pieces from one batch of leather may pass the lamp at a rate such that the surfaces thereof are exposed for approximately fifteen seconds, while pieces from another batch of leather may require as much as two minutes or even more.

Since the endless conveyor 40 (Fig. 4) does not pass entirely around the lamp 10 but only through an arc of about 300°, it is clear that a space is left between the ends of the arc through which ultra-violet radiation might escape without having performed any useful purpose. To obviate this possible loss of radiation there is provided, in the illustrated construction, a reflecting surface arranged to reflect radiation back upon the varnished surfaces of the leather pieces passing through the chamber surrounding the lamp 10. Conveniently, the reflecting surface is provided by two members 190, 192, each having a polished surface adapted to reflect radiation to the leather as described. The polished surface may be made of chromium or of a specially prepared aluminum. While the reflectors 190, 192 may be supported in any convenient manner they are shown attached to a member 194 which extends vertically into the lamp chamber and which may also serve as a supporting means for the lamp 10. As shown, the envelope or shield 12 is attached to the supporting member 194, the lamp 10 being supported within the shield 12 by means of properly spaced abutments 196 which may be made of quartz similar to that used in the manufacture of the shield 12.

In operating the illustrated machine a piece of work is placed upon the belts 130 passing over the table 50. Since all pieces of patent leather are substantially flat when placed upon a flat supporting surface, only a moderate amount of care is necessary in placing the work on the table to insure that it is spread out flat without any folds therein. The piece of work is promptly carried to the wire mesh conveyor 40 which operates to carry each piece of work around the lamp 10 with its varnished surface facing toward the lamp during all of its travel through an arc of about 300° around the lamp 10 during which the varnished surface is subjected to ultra-violet radiation from the lamp, a great portion of which falls upon the work along lines perpendicular to the varnished surface, a small portion of the radiation being reflected upon the work by the V-shaped mirror placed above the lamp at the point where the work enters and leaves the lamp chamber. Following its passage around the lamp each piece of leather is delivered to the set of belts 160 passing over the table 51 whereby the work is delivered to the operator at the rear of the machine.

Having described my invention, what I claim:

as new and desire to secure by Letters Patent of the United States is:

1. That improvement in methods of treating varnished surfaces of sheet material which comprises bending sheet material cylindrically and simultaneously therewith moving said sheet material in a cylindrical path about a source of ultra-violet radiation located at the axis of said cylindrical path, whereby radiation from said source will strike all portions of the exposed surface of the sheet material substantially perpendicularly thereto.
2. In a machine for treating varnished surfaces on flexible sheet material by ultra-violet radiation, a lamp serving as a source of ultra-violet radiation, and means to move flexible sheet material in a circular path around the lamp and simultaneously therewith cause it to conform to said circular path in such manner that all points in the exposed surface of the sheet material are substantially equidistant from the lamp, said means being constructed and arranged to interpose no obstruction between the lamp and the surface to be treated during its travel around the lamp.
3. In a machine for treating varnished surfaces on flexible pieces of leather by ultra-violet radiation, a lamp serving as a source of ultra-violet radiation, a circular guideway having said lamp located at its longitudinal axis, and means to move flexible pieces of varnished leather along said guideway and simultaneously therewith cause the leather to conform to a circular path around the lamp in such manner that radiation from the lamp will strike all portions of the exposed surfaces of the leather pieces substantially perpendicularly thereto, said means being constructed and arranged to engage the unvarnished surface only of each piece of leather thereby to interpose no obstruction between the lamp and the surface to be treated during its travel around the lamp.
4. In a machine for treating varnished surfaces on flexible sheet material by ultra-violet radiation, a lamp serving as a source of ultra-violet radiation, a chamber having a stationary cylindrical wall enclosing said lamp, the lamp being located at the longitudinal axis of the cylindrical wall, and means to move the sheet material in a cylindrical path over and along the inside surface of said cylindrical wall and to maintain said material in uniformly spaced relation to the wall whereby the sheet material is caused to conform to said cylindrical wall and radiation from said lamp will strike all portions of the exposed surface of said sheet material substantially perpendicularly thereto.
5. In a machine for treating varnished surfaces on flexible sheet material by ultra-violet radiation, a lamp serving as a source of ultra-violet radiation, a chamber having a stationary cylindrical wall enclosing said lamp, the lamp being located at the longitudinal axis of the cylindrical wall, a flexible conveyor to move sheet material over and along the inside surface of said cylindrical wall, said flexible conveyor being maintained in uniformly spaced relation to said inside surface, and means to hold the sheet material conformably to the inner concave surface of the flexible conveyor, so that said material is carried in a cylindrical path around said lamp, whereby all points in the exposed surface of said sheet material are maintained substantially equidistant from said source of radiation during travel of the material over said cylindrical wall.
6. In a machine for treating varnished surfaces on flexible sheet material by ultra-violet radiation, a lamp serving as a source of ultra-violet radiation, a chamber for said lamp having a wall of foraminous sheet material arranged in cylindrical form with the lamp at the longitudinal axis thereof, a flexible and foraminous conveyor movable over said wall in a cylindrical path and arranged to move a piece of work into and out of said chamber and around said lamp.
7. In a machine for treating varnished surfaces on flexible sheet material by ultra-violet radiation, a horizontally arranged lamp serving as a source of ultra-violet radiation, means comprising a flexible conveyor to move pieces of varnished leather in a cylindrical path around the lamp, said means having a horizontally arranged portion arranged to transport and to deliver pieces of leather unattached thereto to said flexible conveyor, the latter being constructed and arranged to receive said unattached pieces of leather, and means to hold the pieces of leather in place on said flexible conveyor while they are being carried in succession around said lamp, said holding means being constructed and arranged to maintain the pieces of leather parallel to said conveyor while in said cylindrical path, whereby all portions of the leather are equally spaced from the lamp while travelling around said lamp, said holding means being further constructed and arranged to interpose no obstruction between the lamp and any portion of the varnished surfaces to be treated.
8. In a machine for treating varnished surfaces on flexible sheet material by ultra-violet radiation, a lamp serving as a source of ultra-violet radiation, means including a flexible and foraminous conveyor arranged to travel in a cylindrical path about said lamp for carrying sheet material in said cylindrical path around the lamp, and means co-operating with the foraminous conveyor or for holding such sheet material conformably to the concave surface of the cylindrically arranged conveyor so that the concavely curved surface of the sheet material is directly exposed to radiation from said lamp.
9. In a machine for treating varnished surfaces on flexible sheet material by ultra-violet radiation, a lamp serving as a source of ultra-violet radiation, means comprising a flexible and foraminous conveyor for carrying sheet material in a cylindrical path around the lamp, said conveyor including a foraminous sheet of material upon which the pieces of leather are successively supported, said foraminous sheet being arranged in cylindrical form about the lamp as a central axis, and means co-operating with said foraminous sheet of the conveyor for holding the pieces of work on and everywhere in contact with the concave surface of the cylindrically arranged foraminous sheet so that said pieces of work are exposed uniformly to radiation from said lamp.
10. In a machine for treating varnished surfaces on flexible sheet material by ultra-violet radiation, a lamp serving as a source of ultra-violet radiation, a chamber for said lamp having a wall of foraminous sheet material arranged in cylindrical form with the lamp at the longitudinal axis thereof, a flexible and foraminous conveyor movable over said wall in a cylindrical path and arranged to move a piece of work into and out of said chamber and around said lamp.

whereby every point in the piece of work is equidistant from the lamp during its travel in said cylindrical path, and means for withdrawing air through the foraminous wall and foraminous conveyor, thereby to hold the piece of work upon the conveyor while the latter is passing in the cylindrical path through the lamp chamber.

11. In a machine for treating varnished surfaces on flexible sheet material by ultra-violet radiation, a lamp serving as a source of ultra-violet radiation, a chamber for said lamp having a wall of foraminous sheet material arranged in cylindrical form with the lamp at the longitudinal axis thereof, a flexible and foraminous conveyor movable over said wall in a cylindrical path and arranged to move a piece of work into and out of said chamber and around said lamp, whereby every point in the piece of work is equidistant from the lamp during its travel in said cylindrical path, a chamber enclosing the lamp chamber, and means for withdrawing air from the last-named chamber whereby the tendency to withdraw air from the lamp chamber through the foraminous wall thereof has the effect of holding the piece of work firmly upon the supporting surface of the foraminous conveyor during its travel in the cylindrical path through the lamp chamber.

12. In a machine for treating varnished surfaces on flexible sheet material by ultra-violet radiation, a horizontally arranged lamp serving as a source of ultra-violet radiation, a conveyor mechanism having a horizontal part upon which pieces of work may be loosely placed in close juxtaposition to each other, said conveyor mechanism having also a part to receive pieces of work from said horizontal part and constructed and arranged to move along a cylindrical path about said lamp and to carry pieces of work throughout said cylindrical path, and means to hold the pieces of work parallel to said conveyor while in said cylindrical path, whereby all portions of the work undergoing treatment are equally spaced from said lamp while said portions are disposed on the last-mentioned part of the conveyor mechanism during movement of the latter about said lamp.

13. In a machine for treating varnished surfaces on flexible sheet material by ultra-violet radiation, a horizontally arranged lamp serving as a source of ultra-violet radiation, a conveyor having a horizontal run upon which pieces of work may be loosely placed in close juxtaposition to each other, a flexible conveyor to receive pieces of work from the first mentioned conveyor and constructed and arranged to move along a cylindrical path about said lamp and to carry pieces of work throughout said cylindrical path, and means progressively operative during travel of the work in said cylindrical path to hold the pieces of work parallel to said conveyor while in said cylindrical path, whereby all portions of the work undergoing treatment are equally spaced from said lamp while said portions are disposed on the last-mentioned part of the conveyor during movement of the latter about said lamp, and a delivery means to receive the pieces of work as each in turn is progressively released by the holding means associated with the flexible conveyor.

14. In a machine for treating varnished surfaces on sheet material by ultra-violet radiation, a horizontally arranged lamp serving as a source of ultra-violet radiation, a horizontal conveyor adapted to receive pieces of work held in place

thereon by gravity only, a second conveyor arranged to receive said pieces of work from the first conveyor and to carry them in succession in a cylindrical path about said horizontally arranged lamp, the second conveyor including a sheet of flexible and foraminous material to support the pieces of work, and air suction means operative to hold the pieces of work against the foraminous sheet portion of the second conveyor while the pieces of work are passing around said lamp.

15. In a machine for treating varnished surfaces on flexible sheet material by ultra-violet radiation, a lamp serving as a source of ultra-violet radiation, a flexible conveyor arranged to carry such sheet material in an arc of substantially more than 180° about said lamp, and means to cause said material to conform to the arc while being carried around the lamp, whereby every point in the sheet material is equidistant from the lamp during the travel of the material in said arc.

16. In a machine for treating varnished surfaces on sheet material by ultra-violet radiation, a lamp serving as a source of ultra-violet radiation, means comprising a flexible conveyor to carry a piece of work through an arc of substantially 300° about said lamp, air suction means for holding the pieces of work upon said conveyor, and a mirror arranged substantially to close the space between the ends of said arc, thereby limiting the amount of air entering into the space about the lamp while at the same time serving as a reflector to direct ultra-violet radiation upon the surface of said piece of work while it is traveling about said lamp.

17. In a machine for treating varnished surfaces on flexible sheet material by ultra-violet radiation, a lamp serving as a source of ultra-violet radiation, a conveyor arranged to carry sheet material in a cylindrical path about said lamp to expose surfaces of said material equidistantly with respect to the source of ultra-violet radiation, said conveyor including a flexible sheet of foraminous material, reinforcing members at opposite edges of the flexible foraminous sheet, said reinforcing members and said sheet being securely attached to each other, rotary members for guiding said reinforcing members, rollers in alinement with certain of said rotary members for supporting and guiding said flexible sheet of the conveyor, and air suction means for withdrawing air from the space about the lamp and through said foraminous sheet to hold the pieces of work thereon.

18. In a machine for treating varnished surfaces on flexible sheet material by ultra-violet radiation, a lamp serving as a source of ultra-violet radiation, a conveyor arranged to carry sheet material in a cylindrical path about said lamp to expose surfaces of said material to ultra-violet radiation, said lamp being located at the longitudinal axis of said cylindrical path, so that every point in the piece of work is equidistant from the lamp during its travel in said path, said conveyor including a flexible sheet of foraminous material, a chamber about the lamp having a cylindrical wall of foraminous material, means guiding the flexible sheet portion of the conveyor over the inside concave surface of said cylindrical wall, a chamber enclosing the first-mentioned chamber, and means for withdrawing air from the last-mentioned chamber, whereby the work is held on the foraminous part of the conveyor.

conveyor during travel of the latter in the said cylindrical path.

19. In a machine for treating varnished surfaces on flexible sheet material by ultra-violet radiation, a lamp serving as a source of ultra-violet radiation, a conveyor arranged to carry sheet material about said lamp to expose surfaces of said material to ultra-violet radiation, said conveyor including a flexible sheet of foraminous material, a chamber for the lamp, having a cylindrical wall of foraminous material extending through an arc of approximately 300° about the lamp, said lamp being located at the center of said arc, means to guide the flexible sheet portion of the conveyor over the inside concave surface of said foraminous wall so that all portions of the work are equidistant from the lamp during travel in said arc, a chamber enclosing the first-mentioned chamber, and means for withdrawing air from the last-mentioned chamber.

20. In a machine for treating varnished surfaces on sheet material by ultra-violet radiation, a horizontally arranged lamp, a flexible conveyor having a portion thereof movable in a cylindrical path about said lamp as a central axis, means associated with the conveyor to hold the sheet material concentrically disposed to said cylindrical path so that the exposed surface of the sheet material is everywhere the same distance from the lamp throughout the cylindrical path of its travel about the lamp, said holding means being operative to release the sheet material as the flexible conveyor changes its direction after passing through said cylindrical path, and a delivery means for receiving the sheet material from said flexible conveyor as it is released by the holding means in association with said flexible conveyor.

21. In a machine for treating varnished surfaces on sheet material by ultra-violet radiation, a horizontally arranged lamp, a flexible conveyor having a portion thereof movable in a cylindrical path about said lamp as a central axis, suction means associated with said flexible conveyor and operative to hold the sheet material concentrically disposed upon the conveyor during travel of the latter through said cylindrical path about the lamp, whereby the exposed surface of the sheet material is everywhere the same distance from the lamp throughout the cylindrical path of travel of the material, said suction means serving also to hold the material on the flexible conveyor to a point adjacent to the delivery end of the

flexible conveyor and then to release said material progressively during travel of the latter, and a delivery means to which the flexible conveyor delivers the sheet material as it is progressively released from the action of the suction means. 5

22. In a machine for treating varnished surfaces on sheet material by ultra-violet radiation, a horizontally arranged lamp, a flexible conveyor having a portion thereof movable in a cylindrical path about said lamp as a central axis, a conveyor 10 having a horizontal run upon which pieces of sheet material may be loosely placed to be carried to said flexible conveyor, suction means for holding the sheet material concentrically disposed upon the flexible conveyor while the latter is passing through said cylindrical path about the lamp, whereby the exposed surface of the sheet material is everywhere the same distance from the lamp throughout the cylindrical path of travel of the material, said suction means being arranged to 15 release the material progressively during travel of the latter, and a delivery conveyor having a horizontal run positioned to receive the pieces of sheet material as they are progressively discharged from said flexible conveyor and from 20 the suction means in association therewith.

23. In a machine for treating varnished surfaces on sheet material by ultra-violet radiation, a horizontally arranged lamp, a flexible conveyor having a portion thereof movable in a cylindrical 30 path about said lamp as a central axis, a conveyor having a horizontal run upon which pieces of sheet material may be loosely placed to be fed to said flexible conveyor, suction means for holding the sheet material concentrically disposed upon 35 the flexible conveyor while the latter is passing through said cylindrical path about the lamp, whereby the exposed surface of the sheet material is everywhere the same distance from the lamp throughout the cylindrical path of travel of 40 the material, said suction means being arranged to release the sheet material progressively during travel of the latter, a delivery conveyor having a horizontal run positioned to receive the pieces of sheet material as they are progressively 45 discharged from said flexible conveyor and from the suction means in association therewith, a transfer table located between said flexible conveyor and the horizontal run of the feeding-in conveyor, and a second table between said flexible conveyor 50 and the horizontal run of the delivery conveyor.

JOHN J. BROPHY.
